United States Patent Office

Des. 189,166
Patented Nov. 1, 1960

189,166

PHOTOGRAPHIC SLIDE PROJECTOR

Clare E. Hodgman, Mamaroneck, N.Y., assignor to General Aniline & Film Corporation, New York, N.Y., a corporation of Delaware

Filed Apr. 7, 1959, Ser. No. 55,395

Term of patent 14 years

(Cl. D61—1)

The single figure is a perspective view of a photographic slide projector, showing my new design. The rear and opposite sides, not shown, are conventional.

I claim:

The ornamental design for a photographic slide projector, substantially as shown and described.
